UNITED STATES PATENT OFFICE.

ROMANUS BOHNENBLUST, OF LEONARDVILLE, KANSAS.

WATER MOTOR.

1,402,710.

Specification of Letters Patent. Patented Jan. 3, 1922.

Application filed November 14, 1918. Serial No. 262,459.

To all whom it may concern:

Be it known that I, ROMANUS BOHNENBLUST, a citizen of the United States, residing at Leonardville, in the county of Riley 5 and State of Kansas, have invented certain new and useful Improvements in Water Motors, of which the following is a specification.

This invention relates to power generators and more particularly to water motors.

One of the objects of this invention resides in the provision of a water motor which will generate electricity at a minimum expense.

15 A further object of this invention resides in the provision of a water motor consisting of an embodiment of elements which are controlled to obtain a predetermined amount of power.

20 A still further object of this invention resides in a water motor having adjustable power wheels which carry means for preventing the accumulation of floating rubbish thereon.

25 With these and other objects in view this invention resides in certain novel features of construction and arrangement of elements to be more fully set forth in the specification herewith and pointed out in the appended claims, it being understood 30 that the right is reserved to resort to such minor changes in construction as come within the scope of the claims.

In the accompanying drawings:—

35 Fig. 1 is a plan view of the water motor in operative position in a stream;

Fig. 2 is an enlarged vertical longitudinal sectional view through the float of the water motor showing the mechanism supported thereby in full lines;

40 Fig. 3 is a horizontal sectional view through the hood.

In the present embodiment of this invention the numeral 5 designates a float which 45 consists of a buoyant platform 6 having a housing or hood 10 thereon.

Mounted on the aforesaid hood is an enclosure 12 on the roof of which is secured an electric generator 14 which is enclosed 50 by a housing 16 to protect it from the surrounding damp atmosphere.

Suitably secured within the hood 10 is a rotatable shaft 18 on which is splined a

pulley 20 and sprocket wheels 22. The sprocket wheels 22 are connected to other 55 sprocket wheels 24 on a counter-shaft 26 by suitable chains 28 and are actuated by power wheels 30 on an adjustable shaft 32 through the instrumentality of sprocket wheels 34 and 36 that are connected by suitable chains 38.

The aforesaid power wheels are adjustably retained in operative position to the rear of the counter-shaft by a plurality of arms 40 to the free ends of which is attached the 65 free ends of cables 41 that are wound upon windlasses 42 carried by a shaft 43 that is supported adjacent the top of the hood 10 over the shaft 32.

In order to cause the rotation of the shaft 70 43 and the consequent adjustment of the power wheels, a gear 44 is secured to said shaft 43 for engagement with a worm gear 45 that is manipulated by means of an operating shaft 46.

75 With this mechanism disposed in operative position as heretofore stated and the float anchored by suitable cables 47 in a stream of water it is apparent that the generator 14 will be successfully operated by a 80 belt 48 which transmits the motion of the pulley 20 to a pulley 49 on the generator and through the provision of electric wires 50 the current so generated can be supplied to the surrounding territory.

85 With this invention as herein set forth it is manifest that a power generator is produced which is cheap of manufacture readily operable regardless of the condition of the water and thoroughly reliable in producing 90 the maximum efficiency with a minimum expenditure for maintenance.

Having thus described this invention what I claim is.

1. A water motor comprising a housing 95 adapted to be arranged in the water and adapted to support a mechanism to be operated, a shaft journaled in the casing and extending horizontally thereof, arms pivotally connected with the shaft and extending rearwardly and downwardly therefrom, drums journaled in the lower ends of the arms and adapted to be rotated by the water, driving connection between the drum and shaft, and a power shaft also journaled 100 in the casing and operatively connected 105 in the casing and operatively connected

with the first mentioned shaft and adapted to be connected with the mechanism to be operated.

2. A water operated motor comprising
5 a casing provided with an opening in its bottom a shaft journaled in the casing, a plurality of arms pivoted to the shaft and

extending rearwardly therefrom in proximity to the opening, a plurality of water rotated drums journaled in the arms and extending through the opening.

In testimony whereof I affix my signature.

ROMANUS BOHNENBLUST.
